UNITED STATES PATENT OFFICE.

ADOLPH RUBIN, OF ST. LOUIS, MISSOURI, ASSIGNOR TO SIEBER PRODUCTS MANUFACTURING COMPANY, OF ST. LOUIS, MISSOURI, A CORPORATION OF MISSOURI.

REFRIGERATOR LOCK.

Application filed December 18, 1922. Serial No. 607,723.

To all whom it may concern:

Be it known that I, ADOLPH RUBIN, a citizen of the United States, residing at St. Louis, Missouri, have invented a certain 5 new and useful Improvement in Refrigerator Locks, of which the following is a full, clear, and exact description, such as will enable others skilled in the art to which it appertains to make and use the same.

10 This invention relates to spring-actuated locks of the kind that are used on refrigerators and ice boxes for retaining the door of the refrigerator in its closed position.

15 The main object of my present invention is to provide a refrigerator lock which is so constructed that the latch will not strike against the keeper with which it co-operates every time the door of the refrigerator is closed, thereby reducing the tendency of the 20 keeper to work loose, as generally occurs with a conventional refrigerator lock which is of such construction that the latch strikes the keeper a sharp blow each time the door of the refrigerator is closed.

25 Another object of my invention is to provide a lock for large commercial refrigerators and ice boxes which is equipped with an inside door handle that is connected with the latch of the lock in such a way that there 30 is no tendency for the handle shaft to bind in the door, as so often occurs with locks of the kind that are now used on large commercial refrigerators. Other objects and desirable features of my invention will be hereinafter pointed out.

Figure 1 of the drawings is a rear elevational view of a refrigerator lock constructed in accordance with my invention.

40 Figure 2 is a vertical sectional view, taken on the line 2—2 of Figure 1, looking in the direction indicated by the arrows.

Figure 3 is a vertical sectional view, through a portion of the door of a refrigerator equipped with my improved lock, illustrating how the shaft of the inside door handle is secured to the latch of the lock; and

45 Figure 4 is a side elevational view of the lock, illustrating how the trigger is tripped so as to release the latch and permit it to 50 move into engagement with the keeper at approximately the time the door reaches its closed position.

Referring to the drawings which illustrate the preferred form of my present invention, A designates the casing of the lock,

B designates the latch, C designates the keeper that co-operates with the latch to retain the door in its closed position, D designates the handle on the outside of the door that is used to disengage the latch from the keeper, and G designates the handle on the inside of the door that is used to operate the latch B.

The casing A of the lock may be of any preferred shape or design, but preferably 65 consists of a hollow casting of substantially oblong shape in outline and provided at one side with a laterally-projecting, hollow extension A' to which the latch B is pivotally connected, thereby permitting a relatively 70 long lever to be used to form the latch B of the lock, said casting being open on its inner side and being provided with flanges and lugs 1 through which fastening devices can be passed to secure the casing to the door 75 of the refrigerator. The latch B extends transversely of the casing A with its free end projecting outwardly through an elongated slot 2 in one of the side walls of the casing, and the keeper C is connected to a 80 stationary part of the refrigerator in proximity to the door opening in such a way that a roller 3 on said latch will be seated in a pocket, recess or other irregular surface in the top edge of the keeper C when the 85 door of the refrigerator is in its closed position. The outside handle D of the lock is pivotally mounted on the front wall of the casing A in any preferred manner and is provided at its lower end with an angularly- 90 disposed arm 4 that projects inwardly through an opening in said front wall, as shown in Figure 2, the arm 4 being connected by means of a link 5 with the latch B in such a way that when the upper end 95 of said handle is pulled forwardly (to the right looking at Figure 2) the latch B will be moved upwardly into the position shown in Figure 1.

In the conventional refrigerator locks now 100 in general use the latch of the lock is so arranged that it strikes against the keeper with considerable force each time the door of the refrigerator is closed. This is objectionable, especially in locks that are used on large 105 commercial refrigerators and ice boxes, for the constant hammering of the latch against the keeper causes the keeper to work loose, thus reducing the efficiency of the lock as a means for tightly holding the refrigerator 110

door in its closed position. In order to overcome this objectionable characteristic of the conventional refrigerator lock, I have constructed my improved lock in such a way that the latch B will be maintained in such a position that it will not strike against the keeper C during the operation of closing the door, but, on the contrary, will pass over the keeper or clear same when the door is closing and will thereafter move downwardly into engagement with the keeper at approximately the time the door reaches its fully closed position. I accomplish this desirable result by providing the lock with a spring-actuated trigger E that moves automatically into engagement with the latch B, and thus retains it in its elevated or inoperative position when said latch is lifted or moved upwardly out of engagement with the keeper C by moving the upper end of the handle D forwardly. As shown in Figures 1 and 4, the trigger E is arranged on the inside of the casing A adjacent the side wall of the housing through which the free end of the latch B projects, and is pivotally connected at its lower end to the casing by means of a pintle or pivot pin 6 which may either extend transversely through the side walls of the casing or through one of said side walls, and through a lug 7 on the inside of the casing, as shown in Figure 1. In general design the trigger E resembles a bell crank lever, for it is provided at its lower end with a forwardly-projecting arm 8, shown in broken lines in Figure 4, to which a coiled contractile spring F is connected, the function of said spring being to exert pressure on the trigger E in such a direction that the upper end of said trigger will move into engagement with the underside of the latch B, and thus retain said latch in its elevated position whenever said latch is moved upwardly to disengage it from the keeper C. I also prefer to use the spring F to exert pressure on the latch B in a direction to move said latch downwardly, and thus hold it in engagement with the keeper C, and to this end I connect the upper end of the spring F to a lug 9 on the underside of the latch B. It is immaterial, however, so far as my invention is concerned, whether separate springs are provided for actuating the trigger and the latch, or whether a single spring F is employed for actuating both of said parts. In order to disengage the trigger E from the latch B at approximately the time the door reaches its closed position, the trigger E is provided with a tripping device 10 arranged on the outside of the casing A and connected to the trigger by a portion that passes through the slot 2 in the side wall of the casing through which the free end of the latch B projects, said tripping device 10 being so arranged that it will strike against an abut-

ment 11 on the plate 12 which carries the keeper C. If it is desired to open the door of the refrigerator the upper end of the handle D is pulled forwardly, thereby causing the link 5 to move the free end of the latch B upwardly out of engagement with the keeper C. As soon as the latch B clears the upper end of the trigger or catch E, said trigger will rock rearwardly under the influence of the spring F, and thus cause the upper end of said trigger to be positioned under the latch B, thereby maintaining said latch in its elevated position. Thereafter, when the door is closed, the roller 3 on the latch B passes over the keeper C without touching same or subjecting it to a blow, and just about the time the door reaches its closed position, the end of the tripping device 10 on the trigger strikes against the abutment 11, thereby disengaging the trigger from the latch B, and permitting said latch to move downwardly under the influence of the spring F into engagement with the keeper C.

It is immaterial how the latch B is pivotally mounted on the casing of the lock, but I prefer to provide the laterally-projecting extension A' of the casing with a stud 13, shown in Figure 3, that projects into a hole in the latch B and form the link 5 in such a way that it prevents the latch from moving relatively to the casing in such a direction as to cause the stud 13 to be withdrawn from the hole provided for same in the latch B. In the lock herein shown this is accomplished by providing the link 5 with a pin 14 that projects forwardly through an elongated slot 15 in the latch and providing the lower end of said link with a forwardly-projecting, L-shaped portion 16 whose vertical leg has an elongated slot 17 which receives a combined guiding and retaining device 18 that is connected to the front wall of the casing A. By making the link 5 of this form it virtually acts as a yoke that extends over the latch B, and thus prevents the inner end portion of said latch from becoming disengaged from the stud 13 on which it is mounted, thereby enabling the parts of the lock to be assembled easily and also permitting them to be taken apart easily in the event that it becomes necessary to repair or replace the latch B of the lock.

The handle G on the inside of the refrigerator door is connected with the latch B by means of a horizontally-disposed shaft 19 that extends through the door, as shown in Figure 3. In the conventional refrigerator lock the inside door handle shaft is integrally connected with the latch of the lock. Consequently, there is a tendency for the shaft to bind in the door if the hole through which the shaft extends is not at absolute right angles to the latch of the lock. One object of my invention is to overcome this

defect of the conventional refrigerator lock, and to this end I connect the door handle shaft 19 with the latch B in such a way that said parts are capable of a slight angular movement relatively to each other, thereby eliminating the tendency of the inside door handle shaft to bind in the door. The particular form of connection that is used between the shaft 19 and latch B is immaterial, but I prefer to provide said shaft at one end with a non-circular shaped head 20 that projects into a correspondingly-shaped socket 21 formed in the rear side of the latch B at a point in alignment with the stud 13 on which said latch is pivotally mounted.

Plates 22 and 23 are connected to the outside face and inside face of the refrigerator door 24, so as to form bearings for the shaft 19, and the inside handle G is connected to said shaft by nuts 25 arranged at opposite sides of a portion of said handle through which the shaft 19 passes, said shaft and handle being equipped with grooves in which a key or spline 26 is inserted so as to cause the shaft 19 to turn when the handle G is rocked to the right or to the left. In mounting the lock a hole is first formed in the door for the handle shaft 19. Said shaft is then combined with the latch B by inserting the head 20 on the shaft in the socket 21 of the latch and connecting the outside shaft bearing plate 22 to the casing A of the lock by fastening devices 27, as shown in Figure 3, and the casing A of the lock is then connected to the outer face of the door by fastening devices inserted through the flanges and lugs 1 on said casing. Thereafter, the inside bearing plate 23 is connected to the inner face of the refrigerator door and the inside handle is connected to the shaft 19 by means of the spline 26 and nuts 25.

A refrigerator lock of the construction above described is exceptionally strong and rugged and is inexpensive to manufacture, due to its simple design. The parts of same can be assembled and disassembled easily, and when the lock is in use, the latch of same will not strike against the keeper with which it co-operates each time the refrigerator door is closed, thereby reducing the tendency of the keeper to work loose, as so often occurs in conventional refrigerator locks in which the latch is of such a construction that it strikes the keeper a sharp blow each time the refrigerator door is moved into its closed position.

Having thus described my invention, what I claim as new and desire to secure by Letters Patent is:

1. A refrigerator lock, comprising a spring-actuated, pivotally-mounted latch that is adapted to co-operate with a keeper to retain the refrigerator door in its closed position, a casing that houses a portion of

said latch, a pivotally-mounted handle on the casing, a link inside of said casing connected to said handle and latch for disengaging the latch from the keeper, and a spring-actuated trigger or catch inside of the casing for engaging and holding said latch in an inoperative condition after it has been disengaged from the keeper, said trigger having a portion projecting outwardly through an opening in the casing that is adapted to strike against a stationary part on the refrigerator during the operation of closing the door so as to permit the latch to move into engagement with the keeper.

2. A refrigerator lock, comprising a latch that is adapted to co-operate with a keeper to retain the refrigerator door in its closed position, means for disengaging the latch from the keeper preparatory to opening the door, a trigger or catch that is adapted to move into engagement with the latch and retain it in an inoperative condition after it has been disengaged from the keeper, and a spring combined with said trigger and latch in such a way that it moves the trigger into engagement with the latch after the latch has been disengaged from the keeper and subsequently moves the latch into engagement with the keeper after said trigger has been rendered inoperative.

3. A refrigerator lock, comprising a pivotally mounted latch that is adapted to co-operate with a keeper to retain the refrigerator door in its closed position, a casing that carries said latch, a pivotally mounted handle on the casing, a rigid link pivotally connected to said latch and handle for disengaging the latch from the keeper preparatory to opening the door, and a spring-actuated means arranged inside of said casing for maintaining the latch in a certain position when the refrigerator door is open.

4. A refrigerator lock, comprising a hollow casing provided at one side with a laterally-projecting extension, a latch arranged transversely of said casing inside of same and pivotally connected at one end to said extension, a manually-operable means on the exterior of said casing for moving said latch in one direction, a spring for moving said latch in the opposite direction, and a trigger inside of said casing connected to said spring and adapted to co-operate with said latch for the purpose described.

5. A refrigerator lock, comprising a hollow casing provided at one side with a laterally-projecting extension, a pivotally mounted latch arranged transversely of said casing with its free end projecting through an opening in one wall in the casing, a stud in the extension on the casing that projects into a hole in said latch so as to form a pivot for said latch, a handle on the casing having a portion that projects inwardly through an opening in the casing, a link

- embracing the latch and pivotally connected to same, said link being connected at one end to the inwardly-projecting portion of the handle, and a sliding connection between 5 the opposite end of said link and the casing.
6. A refrigerator lock, comprising a casing adapted to be connected to the door of a refrigerator, a spring-actuated latch in said casing pivotally connected to same by 10 a part on one of said elements that projects into a hole or recess in the other element, an operating handle on the outside of the casing having a portion that projects into the casing, and a link inside of the casing for connecting the handle to said latch, said link extending across said latch and operating to prevent the latch from moving relatively to the casing sufficiently to disturb the pivotal connection between said latch and casing.
- 15 7. A refrigerator lock, comprising a hollow casing adapted to be connected to the door of a refrigerator, a pivotally mounted latch in said casing projecting through an opening in the casing and adapted to operate with a keeper to retain the refrigerator door in its closed position, a pivotally mounted handle on the outside of the casing having a portion that projects into the casing, a link in said casing pivotally connected 20 to said latch and handle, a trigger or catch in said casing adapted to engage the latch and retain it in an inoperative condition after it has been disengaged from the keeper, and a spring combined with said latch and 25 trigger for operating both of said elements, the trigger having a tripping portion that projects outwardly through a hole in the casing.
- 30 8. A lock for refrigerators and ice boxes, comprising a casing that is adapted to be mounted on one side of a refrigerator door,
- a spring-actuated latch on said casing adapted to co-operate with a keeper to retain the door in its closed position, and an operating handle for the latch, and a shaft 45 for said handle journaled in the refrigerator door and provided at one end with a non-circular portion that projects into a correspondingly-shaped socket or opening in the latch.
- 50 9. A lock for refrigerators and ice boxes, comprising a casing that is adapted to be connected to the door of a refrigerator, a pivotally mounted latch carried by said casing, an operating shaft for said latch that is adapted to project through the refrigerator door, said shaft having a loose connection with said latch, and a bearing plate for said shaft detachably connected to said casing and arranged so that it prevents the 55 shaft from separating from said latch.
10. A refrigerator lock, comprising a hollow casing adapted to be connected to a refrigerator door, a pivotally mounted, spring-actuated latch in said casing having its free 60 end projecting through an opening in the casing and adapted to co-operate with a stationary keeper to retain the door of the refrigerator in its closed position, a handle on said casing, a connection between said 65 handle and latch, a pivotally mounted, spring-actuated trigger or catch on the casing adapted to engage the latch and retain it in an inoperative condition after it has been disengaged from the keeper, a tripping 70 device on said trigger, and a shaft adapted to extend through the refrigerator door and provided at one end with a non-circular-shaped portion that projects into a non-circular-shaped opening in the latch for the 75 purpose described.

ADOLPH RUBIN.
